BOTTLE CAP

Eric De Kolb, New York, N.Y., assignor to Coty, Inc.,
New York, N.Y., a corporation of Delaware

Filed Nov. 15, 1961, Ser. No. 67,524

Term of patent 14 years

(Cl. D58—26)

FIG. 1

FIG. 3

FIG. 1 is a side elevational view of a bottle cap showing my new design;

The portions shown in broken lines are for illustrative purposes only.

I claim:

The ornamental design for a bottle cap, substantially as shown and described.
